UNITED STATES PATENT OFFICE.

WATSON SANFORD, OF BROOKLYN, AND GEORGE D. SANFORD, OF PEEKSKILL, NEW YORK.

DESIGN FOR A STOVE.

SPECIFICATION forming part of Design No. 12,626, dated December 20, 1881.

Application filed October 5, 1881. Term of patent 7 years.

To all whom it may concern:

Be it known that we, WATSON SANFORD, of Brooklyn, in the county of Kings and State of New York, and GEORGE D. SANFORD, of Peekskill, in the county of Westchester and said State of New York, have invented a new and original Design in Stoves, of which the following is a specification, reference being had to the accompanying drawings, forming part thereof.

10 **This design consists—**

First. In the molding *s* on the top edge of range *a*; also, on the edge of end shelf, *b*, to the right of the top; also, on the edge of the end door, *c*, to the left of range; also, on edge 15 of projecting shelf *d*, underneath end door; also, on edge of oven-door *e* and long door *f*, in two parts, to left of oven-door; and also on edge of small open-work shelf *g*, underneath long door. This molding (see Fig. 1 of Sheet 2) has a shoulder, 1, and below such shoulder 20 a curve, 2.

Second. In the bracket *u*, which is recessed from the edge of left end, *i*, of range where doors are, which bracket has on its edge two shoulders, 4 and 5, and an intermediate convex surface, 6. (See Fig. 3 of Sheet 2 of drawings.)

Third. In the design *l* on said oven-door surrounding the lozenge-shaped design *k*, and also 25 long door *f*.

Fourth. In the lozenge-shaped design *k*, in

combination with the design *l* on oven-door, either with or without the words "Brie-a-Brac."

Fifth. In the square molding *m*, panels *n n*, and round corner *o* on the feet of said range. 35

Sixth. The general design of the range.

We claim—

1. The molding *s* on top edges of range *a*, end shelf, *b*, end door, *c*, and projecting shelf *d* below end door, on oven-door *e*, and long 40 doors *f*, in two parts, and on small open-work shelf *g* underneath long door, substantially as described.

2. The bracket *u*, recessed from the edge of left end, *i*, of range, substantially as described. 45

3. The design *l* on said oven-door surrounding the lozenge-shaped design *k*, substantially as described.

4. The lozenge-shaped design *k*, in combination with the design *l* on oven-door, substantially as described. 50

5. The square molding *m*, panels *n n*, and round corner *o* on the feet of the range, substantially as described.

6. The design of range, all substantially as 55 above described and set forth.

WATSON SANFORD.
GEORGE D. SANFORD.
